UNITED STATES PATENT OFFICE.

OSCAR HANDLER, OF NEW YORK, N. Y.

MACHINE FOR THE PURPOSE OF CHANGING THE FEET ON WATCH DIALS.

Application filed December 5, 1922. Serial No. 605,122.

To all whom it may concern:

Be it known that I, OSCAR HANDLER, a citizen of the Republic of Poland, and residing at New York, in the county of New York and State of New York, have invented certain new and useful Improvements in Machines for the Purpose of Changing the Feet on Watch Dials, of which the following is a specification.

10 My invention is a machine for the purpose of changing the feet on watch dials, and it consists in the combinations, constructions and arrangements herein described and claimed.

15 An object of the invention is to provide a reliable and efficient device by the use of which a watch dial can be transferred from one watch to another and accurately positioned on the watch to which it is transferred.

20 A further object of the invention is to provide a device of the character described, which can be used to attain the foregoing object by workmen possessing no unusual skill or experience.

25 Other objects and advantages will be apparent from the following description, considered in conjunction with the accompanying drawings, in which:

30 Figure 1 is a front view of the device embodying the invention in applied position in respect to a watch dial,

Figure 2 is an edge view of the structure exhibited in Figure 1,

35 Figure 3 is a rear view of the same structure,

Figure 4 is a slightly enlarged section substantially along the line 4—4 of Figure 1, and

40 Figure 5 is a plan view of a tool which is adapted to be used in tightening the connections at certain joints of the device.

45 A device embodying the invention comprises a handle 1, having a socket 2 in its forward end. A pair of elongated spring clamping members 3 and 4 respectively have their rearward end portions secured in the socket 2 by any suitable fastening means, such as that indicated at 5. The forward end portions of the spring clamping members 3 and 4 diverge apart as best seen in Figure 2, and each has the forward end portion thereof reduced in width as indicated at 3^a and 4^a, respectively.

50 The reduced end portions 3^a and 4^a of the clamping members are adapted to straddle

a watch dial 6, the reduced portion 3^a being disposed at the front of the watch dial. A pivot element 7 having a tapering end portion adapted to enter the usual central opening of the watch dial has a shank 8 which extends through an opening in the portion 3^a adjacent to its extremity. The shank 8 also extends through an opening in a pointer 9 which is held flatwise against the extreme end portion of the spring clamping arm 3 by a knurled nut or cap 10 which threadedly engages the shank 8. The pointer 9 is adapted to be swung about the axis of the shank 8 and therefore about the axis of the dial 6 when the thumb nut 10 has been loosened slightly to point to any one of the usual graduations on the front face of the dial, and the pointer 9 then may be secured in adjusted position with respect to the selected graduation by tightening the thumb nut 10.

55 The reduced portion 4^a of the second spring clamping arm extends at the rear of the dial 6 and carries a clamping member 11 which is secured by a fastening element 12 to the reduced portion 4^a of the spring clamping arm in position on the latter to abut the central portion of the dial so that the adjacent end of the pivot element 7 is received in a cavity 13 in the adjacent face of the member 11.

60 The divergent portions of the spring clamping arms 3 and 4 are provided with alined slots 14 and 15 respectively which extend longitudinally of the clamping arms and through which the shank of a screw 16 extends, the head of the screw abutting the spring arm 3, and a knurled nut 17 being screwed on the shank of the screw against the spring clamping member 4. It will be manifest that the spring clamping arms will be forced toward each other when the nut 17 is tightened so that the central portion of the dial 6 will be held firmly between the pivot element 7 and the clamping member 11.

65 The spring clamping member 4 is provided adjacent to the side edges thereof, and at the juncture of the reduced portion 4^a and the remainder of the spring clamping member 4 with transversely alined stud projections or screws which serve as pivot elements for a pair of swingable arms 18. Nuts 19 threadedly engage the outer ends 70 of the pivot elements just referred to, and may be tightened to secure the arms 18 in

adjusted angular relation to the clamping member 4. The arms 18 are provided at their outer ends with laterally extending pivot elements which extend through openings in secondary swingable arms 20, nuts 21 being in threaded engagement with the pivot elements connecting the arms 20 with the arms 18 and being adjustable to secure the arms 20 in adjusted angular relation to the arms 18. The nuts 19 and 21 are provided with head portions, each of which has a transverse opening, as indicated at 22 adapted to be engaged by a reduced end portion 23 of a turning tool or key 24, shown in Figure 5, whereby the nuts 19 and 21 can be conveniently turned to tighten or loosen the same, as desired.

The arms 20 are provided adjacent to their free ends with transverse openings 25, each of which is adapted to receive the extending end portion of a stud projection 26 on the rear face of the watch dial. The openings 25 are intersected by lateral threaded bores in which the shanks of set screws 27 are threaded for locking the arms 20 to the stud projections 26.

When the arms 20 have been made fast to the stud projections 26 and the clamping members 3 and 4 have been secured in such position in respect to each other that the watch dial is held firmly between the elements 7 and 11, the operator can make the exact measurements on the watch to which the dial is to be transferred and can determine the exact space between the feet on the dial before it has been removed from the watch.

I claim:

1. A device of the character described, comprising a handle, a pair of elongated spring clamping members carried by the handle and adapted to straddle the dial of a watch, adjustable means connecting the clamping members, and pivoted arms carried by one of said clamping members.

2. A device of the character described, comprising a handle, a pair of elongated spring clamping members carried by the handle and adapted to straddle the dial of a watch, adjustable means connecting the clamping members, pivoted arms carried by one of said clamping members, and means whereby said pivoted arms can be releasably held against swinging relatively to said one spring clamping member.

3. A device of the character described, comprising a handle, a pair of elongated spring clamping members carried by the handle and adapted to straddle the dial of a watch, adjustable means connecting the clamping members, pivoted arms carried by one of said clamping members, and a pointer pivotally supported on the other of said spring clamping members.

4. A device of the character described,

comprising a handle, a pair of elongated spring clamping members carried by the handle, and adapted to straddle the dial of a watch, a pivot element carried by one of said spring clamping members in position to enter the central opening of the watch dial, a clamping element carried by the other of said spring clamping members for engaging the central portion of the opposite face of the dial and having a depression for the reception of the adjacent end of said pivot element, and adjustable means connecting said spring clamping members.

5. A device of the character described, comprising a handle, a pair of elongated spring clamping members carried by the handle, and adapted to straddle the dial of a watch, a pivot element carried by one of said spring clamping members in position to enter the central opening of the watch dial, a clamping element carried by the other of said spring clamping members for engaging the central portion of the opposite face of the dial and having a depression for the reception of the adjacent end of said pivot element, adjustable means connecting said spring clamping members, and a pointer carried by said spring clamping member for swinging movement about the axis of said pivot element.

6. A device of the character described, comprising a handle, a pair of elongated spring clamping members carried by said handle and adapted to straddle the dial of a watch, means at the free ends of said clamping members for engaging the central portion of a watch dial at opposite sides of the latter, and swingable arms carried by one of said spring clamping members for engaging with projections on the adjacent face of said dial.

7. A device of the character described, comprising a handle, a pair of elongated spring clamping members carried by said handle and adapted to straddle the dial of a watch, means at the free ends of said clamping members for engaging the central portion of a watch dial at opposite sides of the latter, swingable arms carried by one of said spring clamping members for engaging with projections on the adjacent face of said dial, and means for releasably holding said projection engaging members against movement relatively to said spring clamping member.

8. A device of the character described, comprising a handle, a pair of elongated spring clamping members carried by the handle and adapted to be secured at their outer ends in clamping relation to opposite sides of the central portion of a watch dial, a pointer carried by one of said spring clamping members for swinging movement about the axis of the dial, a pair of pivoted arms carried by the other elongated spring

clamping member, a pair of other pivoted arms carried at the outer ends of the first named pivoted arms, said last named pivoted arms having openings at their free ends for engaging with projections on the adjacent face of the dial.

9. A device of the character described, comprising a handle, a pair of elongated spring clamping members carried by the handle and adapted to be secured at their outer ends in clamping relation to opposite sides of the central portion of a watch dial, a pointer carried by one of said spring clamping members for swinging movement about the axis of the dial, a pair of pivoted arms carried by the other elongated spring clamping member, a pair of other pivoted arms carried at the outer ends of the first named pivoted arms, said last named pivoted arms having openings at their free ends for engaging with projections on the adjacent face of the dial, and means for securing said second named pivoted arms to said projections.

10. A device of the character described, comprising a handle, a pair of elongated spring clamping members carried by the handle and adapted to be secured at their outer ends in clamping relation to opposite sides of the central portion of a watch dial, 25 a pointer carried by one of said spring clamping members for swinging movement about the axis of the dial, a pair of pivoted arms carried by the other elongated spring clamping member, a pair of other pivoted arms carried at the outer ends of the first named pivoted arms, said last named pivoted arms having openings at their free ends for engaging with projections 30 of the adjacent face of the dial, means whereby said first named pivoted arms can be secured to said second spring clamping member in adjusted angular relation to the latter, and other means whereby said second named pivoted arms can be secured to the 35 first named pivoted arms in adjusted angular relation to the latter. 40 45

OSCAR HANDLER.
